UNITED STATES PATENT OFFICE.

LORENZ A. DEUTHER, OF BUFFALO, NEW YORK.

MACHINE FOR MAKING PICTURE-BACKBOARDS, &c.

SPECIFICATION forming part of Letters Patent No. 689,466, dated December 24, 1901.

Application filed May 17, 1900. Serial No. 17,042. (No model.)

To all whom it may concern:

Be it known that I, LORENZ A. DEUTHER, a citizen of the United States, residing at Buffalo, in the county of Erie and State of New York, have invented certain new and useful Improvements in Machines for Making Picture-Backboards and the Like, of which the following is a specification.

My invention relates to a machine for making laminated boards in which a plurality of slats of wood or other suitable material are cemented between two sheets of paper or other flexible material; and the object is to produce a machine having mechanism for feeding the slats, mechanism for coating the paper or other flexible material with cement, and mechanism for assembling the slats between the coated sheets.

For a full understanding of the merits and advantages of the invention reference is to be had to the accompanying drawings and the following description.

The invention is susceptible to various changes in the form, proportion, and minor details of construction without departing from the principle or sacrificing any of the advantages thereof, and to a full disclosure of the invention an adaptation thereof is shown in the accompanying drawings, in which—

Figure 1 is a side elevation of my improved machine. Fig. 2 is an enlarged side elevation of the forward part of the machine with the operating-gearing removed. Fig. 3 is a vertical longitudinal section on or about line *a a*, Fig. 4. Fig. 4 is a top plan view with the slat-receiving rolls and belts removed. Fig. 5 is a detail view of one of the guides employed for retaining the slats in a horizontal position.

Referring to the drawings in detail, like numerals designate like parts.

The frame 1 of the machine is provided with hangers 2 and 3, in which shafts of several of the operating parts are journaled. The shaft 4 is journaled in the boxes 5 in the lower portion of the hangers 2 and may be adjusted vertically by means of the adjusting-screws 6. Shafts 7 and 8, carrying pulleys 9, are journaled in the upper portions of the hangers. Vertical supports or frame-pieces 10 are arranged on each side of the pulley 9 and are provided with forked lower ends, which fit

over the horizontal cross-bars 11 and 12, thereby holding the supports or frame-pieces in vertical position. Adjustable pulleys 13 are journaled in the upper portions of the supports or frame-pieces and are operatively connected with the pulleys 9 by the endless belts 14. The upper pulleys 13 are vertically adjusted to tighten the belts by the adjusting-screws 15.

Two sets of the upper and lower adjusting-pulleys are preferably employed and the slats are arranged between the belts that they carry, and fed vertically downward.

A means is provided for maintaining the ends of the slats in alinement, which preferably consists of two vertical arms 16, which extend upward from the frame on each side of the belts and pulleys and in the same vertical plane as the space between the belts.

Vertical stops or standards 17, having horizontal pins 20 adjustably fitting in openings in enlargements 21 of the arms 16, serve as alining-stops for the slats and are adapted to be adjusted toward or from each other to receive different lengths of slats.

The pins 20 are secured in their adjusted position in the enlargements 21 by the set-screws 22.

Toothed feeding-wheels 23 are mounted upon the horizontal shaft 24, journaled in the frame, and take the slats as they come from the vertical belt-feeding mechanism and feed them upon the horizontal table or top 25 of the machine-frame. As the toothed wheels 23 are revolved in the direction indicated by the arrow the slat is carried from under the stack and is pushed between the guides 26 and 27, the lower guides 26 running parallel with the machine, forming a bed which receives the slats from the stack as they are successively fed to it by the toothed wheel 23 and the adjustable guides 27, which are secured to the cross-rods 11 and 29 and are rigidly held in place by the nuts 30, just sufficient space being left between the guides 26 and guides 27 to permit the slats to pass loosely between them, as shown in the drawings. As the slats are carried from the stack and between the guides 26 and 27 they pass between the feed-wheels 31 and 32, mounted in the hangers 3. As many of these wheels 31 and 32 may be used as desired, and these

are mounted parallel with the slats passing between them, and as they engage each slat they force it forward to the depression or cementing rollers 33 and 34. These depression or cementing rollers 33 and 34 are mounted directly over each other, similar to the feeding-wheels 31 and 32, and the paper sheets 35 and 36, which are to be glued to the slats, are fed to the machine over these rollers 33 and 34, the pressure-rollers causing the paper to firmly adhere to the slats.

Referring to Fig. 1, 37 represents reservoirs for holding the liquid glue, in which are mounted the supply-rollers 38.

15 The paper sheets 35 and 36 are preferably supported in roll form upon spools 39 and are coated with glue or other cement as they pass over the coating or supply rollers 38, being held in contact with the supply-rollers by the 20 rubber strip 41, which is mounted in the support 42, (see Fig. 1,) from whence the paper passes over guide-rollers 43, as seen in the drawings, and to the depression or cementing rollers 33 and 34.

25 The slats are first fed vertically into the machine between the belts 14, as above described, and stacked over the toothed feeding-wheels 23, where they are successively carried between the guides 26 and 27 and 30 passing between the feed-wheels 31 and 32, where they are forced forward to the depression or cementing rollers 33 and 34. These rollers 33 and 34, over which the glued paper passes, are loosely mounted in the hangers 3 35 and are caused to revolve by the passage of the slats between them, thus causing the slats to press closely against each other as they are forced along by the wheels 31 and 32, and the glued paper sheets 35 and 36, which are 40 now pressed upon the slats as they pass between the rollers 33 and 34, hold the slats firmly in place, thus forming a stiff antiwarping backing.

I claim as my invention—

45 1. A machine for making picture - backboards and the like, having feeding mechanism, a toothed wheel for taking the slats as they come from said feeding mechanism, and means for pressing and cementing the slats 50 between interposed cement-coated sheets of material.

55 2. A machine for making picture - backboards and the like, in which sheets of material are cemented upon opposite faces of a series of slats, comprising feeding mechanism by which the slats are introduced in face-to-face position, assembling mechanism for cementing the slats between cement-coated sheets of material, and means for moving the 60 slats from a face-to-face position to an edge-to-edge position before feeding them into the assembling mechanism.

65 3. A machine for making picture - backboards and the like, in which sheets of material are cemented upon opposite faces of a series of slats, comprising feeding mechanism by which the slats are introduced in face-to-

face position, assembling mechanism for cementing the slats between cement-coated sheets of material, and a toothed wheel arranged between the feeding mechanism and the assembling mechanism for moving the slats from a face-to-face position to an edge-to-edge position before feeding them into the assembling mechanism.

4. A machine for making picture - backboards and the like, in which sheets of material are cemented upon opposite faces of a series of slats, comprising two feed-belts between which the slats are introduced, assembling mechanism for cementing the slats between cement-coated sheets of material, and a toothed wheel for carrying the slats from the feed-belts to the assembling mechanism.

5. A machine for making picture - backboards and the like, having two feed-belts between which the slats are arranged in face-to-face position, a toothed wheel arranged to take the slats as they come from the feed-belts and arrange them in edge-to-edge position, intermediate push-rollers in the rear of the toothed wheel, means for coating the surface of sheets of material with cement, and tension-rollers in the rear of the push-rollers for pressing and cementing the slats between 95 interposed cement-coated sheets of material.

6. A machine for making picture - backboards and the like, having two vertical feed-belts between which the slats are arranged in face-to-face position, a toothed wheel arranged to take the slats as they come from the feed-belts and arrange them in edge-to-edge position, intermediate push-rollers in the rear of the toothed wheel, means for coating the surface of sheets of material with cement, and tension-rollers in the rear of the push-rollers for pressing and cementing the slats between interposed cement-coated sheets of material.

7. A machine for making picture - backboards and the like, having vertical feed-belts between which slats are arranged in vertical position and fed vertically downward, a toothed wheel between said forward feed-belts for taking the slats as they come therefrom and arranging them edge to edge, intermediate push-rollers in the rear of the toothed wheel, means for coating the surface of sheets of material with cement and tension-rollers in the rear of the push-rollers for 115 pressing and cementing the slats between interposed cement-coated sheets of material.

8. A machine for making picture - backboards and the like, in which slats are cemented between interposed sheets of material, comprising pairs of feed-rollers connected by vertical belts between which the slats are arranged in vertical position and fed vertically downward, a toothed wheel beneath the feed-belts for taking the slats as they 120 come therefrom and arranging them loosely edge to edge, intermediate push-rollers in the rear of the toothed wheel for pressing the edges of the slats into close contact, cement-

rollers for coating the surface of the sheets of material, and tension-rollers in the rear of the push-rollers for pressing and cementing the slats between interposed sheets of material.

9. In a machine for the manufacture of laminated backing, a plurality of endless belts mounted within a frame and arranged to exert a downward pressure upon a stack 10 of slats placed between them, toothed feeding-wheels mounted beneath said slats and adapted to successively engage the lower slat, and carry it upon the bed of the machine, a

series of secondary feeding-wheels adapted to press the slats closely together upon the bed 15 and force them between depression-rollers, said depression-rollers being arranged to exert a pressure upon glue-coated paper fed over them and adhered to each side of the slats as they pass between the depression- 20 rollers, substantially as shown and described.
